UNITED STATES PATENT OFFICE.

RICHARD GREENHALGH AND JOSIAH GREENHALGH, OF OLDSHAM, ENGLAND.

MACHINE FOR OPENING AND CLEANING COTTON OR OTHER FIBERS.

No. 903,969.

Specification of Letters Patent.

Patented Nov. 17, 1908.

Application filed December 10, 1904. Serial No. 236,332.

To all whom it may concern:

Be it known that we, RICHARD GREENHALGH and JOSIAH GREENHALGH, subjects of Great Britain, residing at Oldham, in the 5 county of Lancaster, Kingdom of Great Britain, have invented new and useful Improvements in Machines for Opening and Cleaning Cotton or Other Fibers, of which the following is a specification.

10 Our invention relates to that type of apparatus for opening and cleaning cotton, cotton waste, wool and the like, known as "willows".

15 The object of our invention is firstly, to provide the inlet of the machine with an intermittently rotated feeder adapted to push the fibers to be treated into the inlet of the machine and capable of being charged either by hand or mechanically while it feeds the 20 machine. This rotary feeder insures the fibers being fed into the machine more quickly and positively and obviates the necessity of lowering the grid when feeding.

25 The object of our invention is secondly, to provide an improved form of delivery device whereby the fibers are freed from impurities which they may still contain while being delivered, whereby the efficiency and capacity of such machines is greatly improved.

30 We attain these objects by the mechanism illustrated in the accompanying two sheets of drawings, in which—

35 Figure 1 is a side view, and Fig. 2 a plan of the feeding and delivery end of a "willow" constructed in accordance with our invention, Figs. 3, 4, 5, 6, 7 and 8 are sectional side views showing various forms of our improved feeding device.

40 Similar letters refer to similar parts throughout the several views.

45 In carrying out our invention and referring to Figs. 1, 2 and 3, this rotary feeder for instance, consists of a plain trough *a* forming in cross section an arc of a circle employed in front of the inlet *b* of the machine having raised ends *c* and of a blade *d* carried by a shaft *e* suitably mounted and adapted to rotate in the trough *a* and push 50 the fibers to be treated previously placed into the same through the inlet *b* into the machine, the said trough being capable of being charged while the said blade feeds the machine.

55 The blade *d* may be secured to the shaft *e*

by means of brackets *f*, as shown in Fig. 3, or in any other suitable manner.

According to another form, see Fig. 4, our rotary feeder may consist of a rotary drum *g* having one or more blades *d* radiating 60 from the center which divide the drum into one or more compartments *h* into which the fibers to be treated are placed, the inlet *i* of each compartment when opposite the inlet *b* of the machine serving also as outlet and allowing the fibers in the respective compartment to pass through the inlet *b* into the machine while at the same time the other compartments of the drum can be charged 65 with fibers.

70 The same result, as that shown in Fig. 4, may be attained in the manner shown in Fig. 5, by simply securing two blades *d* to the feeder shaft *e* (which blades may be curved).

75 The rotary feeder described may be rotated intermittently or continuously in any convenient manner, say as in the present instance intermittently, by means of a chain *k* and chain wheels *l* actuated from the intermittently rotated deliver door motion wheel *m*, see Figs. 1 and 2.

80 The rotary feeder described may be charged with fibers direct by hand, or automatically as shown in Fig. 6, by employing 85 in front thereof, a beater *n* rotating over a grid *o* in connection with a pair of feed rollers *p* and a feed lattice *q* whereby the rotary feeder may be continuously supplied 90 with the fibers to be treated and the latter freed from a certain amount of impurities before entering the feeder, the said impurities being caught by a suitable chute *r* and thereby conveyed underneath the grid of the machine.

95 In some cases we may dispense with the beater *n* and grid *o*, as shown in Fig. 7, and only use the feed rollers *p* and lattice *q* in connection with the said trough, or use the lattice *q* alone, as shown in Fig. 8.

100 In some cases we may furnish the machine inlet *b* with a door *s* adapted to close it while willowing. This door, suitably guided at each end, is closed and opened, say by means of cams *t*, operating levers *u* in which latter the door ends *v* pivotally engage, see Fig. 1. In Figs. 3, 4, 5, 7 and 8 such door is shown closed, and in Fig. 6 open.

110 Our invention consists in the second place in dispensing with the lattice by which the

treated fibers hitherto have been delivered and employing in lieu thereof in front of the delivery door *w*, Figs. 1 and 2, a spiral conveyer *x* adapted to rotate in a perforated 5 trough *y* and deliver the treated fibers out of the machine, the said perforated trough permitting small impurities which may be still left in the treated fibers to leave them by dropping through the perforations in the 10 trough *y*.

What we claim as our invention and desire to secure by Letters Patent, is—

1. In a machine for opening and cleaning cotton and other fibers, a plain fiber trough 15 in cross section forming an arc of a circle with inner edge adjacent to the machine inlet and adapted to receive the fibers at its outer edge, an intermittently rotated feeder mounted concentrically in the said trough to 20 push at each intermittent rotation the fibers in a lump direct into the said inlet from whence they are drawn into the machine to be operated upon and at the same time permit of the said trough receiving a fresh 25 charge of fibers, all combined substantially as and for the purpose set forth.

2. In a machine for opening and cleaning cotton and other fibers, a plain fiber trough in cross section forming an arc of a circle 30 with inner edge adjacent to the machine inlet and adapted to receive the fibers at its outer edge, an intermittently rotated feeder mounted concentrically in the said trough consisting of a shaft carrying a blade to push 35 at each intermittent rotation the fibers in a lump direct into the said inlet from whence they are drawn into the machine to be operated upon and at the same time permit of the said trough receiving a fresh charge of 40 fibers, all combined substantially as and for the purpose set forth.

3. In a machine for opening and cleaning cotton and other fibers, in combination a

plain trough secured outside along the machine inlet for receiving the fibers to be fed 45 into the machine and an intermittently rotated feeder in the said trough which during each intermittent rotation pushes the fibers from the latter in a lump direct into the said 50 inlet and a lattice for supplying the said feeder, all substantially as and for the purpose set forth.

4. In a machine for opening and cleaning cotton and other fibers, in combination a plain trough secured outside along the machine 55 inlet for receiving the fibers to be fed into the machine and an intermittently rotated feeder in the said trough which during each intermittent rotation pushes the fibers from the latter in a lump direct into the said 60 inlet, a pair of feed rollers adjacent thereto and a lattice for feeding the fibers between the said rollers, all substantially as and for the purpose set forth.

5. In a machine for opening and cleaning 65 cotton and other fibers, in combination a trough secured outside along the machine inlet for receiving the fibers to be fed, an intermittently rotated feeder in the said trough adapted to push the fibers from the latter in 70 portions at intervals direct into the said inlet, a grid adjacent to the said trough and a beater, a pair of feed rollers adjacent to the said grid and a lattice in connection with the said rollers, the said beater passing the 75 fibers from the said rollers into the said trough, all substantially as and for the purpose set forth.

In testimony whereof we have signed our names to this specification in the presence of 80 two subscribing witnesses.

RICHARD GREENHALGH.
JOSIAH GREENHALGH.
